RUBBER SHOE

Leslie H. L'Hollier, Waltham, Mass., assignor to
 The B. F. Goodrich Company, New York, N. Y.,
 a corporation of New York

Application March 25, 1932, Serial No. 601,073

2 Claims. (Cl. 36—7.3)

This invention relates to shoes made of rubber and fabric and more particularly to an over-shoe adapted to be worn over low or oxford type shoes.

5 The principal objects of the invention are to provide neatness and simplicity of construction and adaptability to the movements of the foot without detracting from the appearance of the shoe.

10 Another object is to provide a shoe having a vent at the front thereof with means for preventing tearing of the vent on removing or replacing the shoe.

Other objects will appear from the following 15 description and the accompanying drawing.

In the drawing;

Fig. 1 is a perspective view of the shoe.

Fig. 2 is a front elevation thereof with the strap buttoned.

20 Fig. 3 is a similar view with the strap open.

Fig. 4 is a cross section on line 4—4 of Fig. 2.

Referring to the drawing:

The numeral 10 designates a one-piece vamp and quarters comprising the flexible upper of 25 the shoe and 11 designates a one-piece lining coextensive therewith.

In order to provide for easy removal and replacement of the shoe the upper 10 is provided with a vent 12 in the front thereof which extends 30 only part way to the toe of the shoe. To provide against further extension of the vent by tearing a rip-resisting reinforcement comprising a U-shaped cord 13 is built into the shoe between the upper 10 and lining 11 across the path of possible 35 tear. This cord may be of plied yarns impregnated with rubber or may be made by rolling a strip of rubberized fabric on itself.

In order to normally conceal the vent 12, to provide for resilient conformity to the foot, to 40 resist spreading of the vent, and to provide an

ornamental appearance, an elastic strap 14 of rubber material adapted to bridge the vent is fastened to the upper at one side of the shoe as at 15 and is removably fastened at the other side by means of a snap-fastener member 16 riveted to the upper and a mating snap-fastener member 17 mounted on the strap. The strap 14 may be provided with an elastic lining 18 of knitted fabric to prevent chafing of the upper and reduce friction between the upper and the 65 strap.

By this simple construction I provide economy of manufacture in conjunction with long wearing qualities, ease of application, snugness of fit and comfort throughout a substantial range of boot shapes.

70 By attaching the strap to the upper only at its narrowed ends above the ball of the foot, as shown, and forming the strap of greater width at its center so as to cross the line of normal wrinkling of the shoe across the ball, undesirable gaping of the strap is avoided and wrinkled appearance of the shoe when the foot is flexed is prevented.

I claim:

1. A shoe made of rubber and fabric and comprising a flexible upper having a vent formed in the front thereof extending toward the toe, a lining attached to said upper, and a non-elastic rip-preventing cord extending across the upper below and around said vent between the upper and lining.

2. A shoe made of rubber and fabric and comprising a flexible upper having a vent formed in the front thereof extending toward the toe, a lining attached to said upper, and a non-elastic rip-preventing cord of rolled fibrous material extending across the upper below and around said vent between the upper and the lining.
